UNITED STATES PATENT OFFICE.

WILL F. SMITH, OF BROOKLYN, NEW YORK, ASSIGNOR TO THE GOVERNOR FASTENER COMPANY, OF NEW YORK, N. Y., A COPARTNERSHIP CONSISTING OF KATE SCHEINMAN AND LOUIS J. SCHEINMAN.

NECKTIE.

Application filed February 16, 1924. Serial No. 693,165.

To all whom it may concern:

Be it known that I, WILL F. SMITH, a citizen of the United States and resident of the borough of Brooklyn, county of Kings, city and State of New York, have invented certain new and useful Improvements in Neckties, of which the following is a specification.

My invention relates to neckties of the ready-made type, and has for its object to provide a novel construction and arrangement of neckband and fastening means whereby the necktie is secured in place upon the wearer. Other more specific objects of the invention will appear more fully from the description hereinafter.

In the accompanying drawings, which show an example of the invention without defining its limits, Fig. 1 is a rear view of the necktie with the neckband straightened out. Fig. 2 is an edge view thereof; Fig. 3 is a view illustrating the tie in combination with a collar with which it may be worn and Fig. 4 is a detail sectional view of one end of the neckband.

The illustrated example shows the invention applied to bow ties for which it is particularly adapted, although it is to be understood that the improved neckband and fastening means may also be used to advantage with other types of neckties.

The improved neckband and fastening means comprises a band 10 which may be constructed wholly of elastic material as shown or be made otherwise elastic in any conventional manner, said band preferably being provided with the well-known slide 11 for adjusting the length thereof. At one end the band 10 is provided with a hook 12 which, as shown, may have a slot 13 for slidably accommodating said band as shown in Fig. 1. At its other end the band 10 is attached to a fastening device comprising a loop 14 and a member 15 extending in offset relation to said loop and having an open recess 16, said member being connected with the loop 14 by a transverse web 17 as shown in Fig. 4; in the preferred construction the loop 14, member 15, and transverse web 16

by means of metallic eyelet or rivet 18 as shown. The neckband and its fastening devices are particularly adapted for combination with bow ties which, as shown in the drawings, may consist of the customary body 19 permanently fashioned in the form of a bow and including the customary knot 20 encircling the body at its central portion.

In practice the neck band 10 has that end at which the compound fastening device 14-15 is located, fastened to the tie body 19 preferably beneath the knot 20 and in any suitable manner as by sewing. The arrangement is such that the loop 14 of the compound fastening device is positioned beyond the knot 20 at the back of the tie so as to be free therefrom and readily accessible, while the recessed member 15 projects over the knot 20 with the recess 16 opening upwardly in the wearing position of the tie. Thus the hook 12 is located at the free end of the band 10 in such a position as to be easily engaged with the loop 14 to maintain the tie in position upon the wearer.

With ties of the ready-made type which are permanently tied, great difficulty is encountered in combining the tie with collars of the turn-over type; if the tie is combined with such a collar before the latter is attached to the shirt, said tie continually falls out of place while if the combination is attempted after the collar has been connected with the neckband then the tie is placed in its intended position only with the greatest of effort particularly with stiff turn-over collars. This difficulty is entirely overcome with the present improvement. As shown in Fig. 3 the tie may be temporarily combined with the collar *a* by placing the body 19 over the end edge *b* thereof, then stretching the band 10 around the collar and engaging the hook 12 with the other end edge *c* thereof. In this way the tension of the band 10 draws the knot 20 against the edge *b* and the hook 12 against the edge *c* and firmly holds the parts in combination with the collar *a*; the latter may thus be freely manipulated and attached to the shirt in the customary manner without paying any attention to the tie which is automatically held in place upon said collar during this operation. When the attachment of the collar *a* to the shirt has been completed the tie is drawn away from the edge *b* and the hook

12 is engaged with the loop 14; either previously to this connection of the hook 12 and loop 14 or subsequently thereto, as desired, the recess 16 of the member 15 is forced over 5 the collar button at the front of the neck band. The tie is now securely fixed in place against shifting in any direction, either circumferentially of the collar or upwardly thereon. With the improvements described 10 and shown herein, the operation of combining the tie with the collar and the attachment thereof to the shirt is reduced to the simplest form and is effected without any effort other than that required to combine 15 the collar with the shirt.

Various changes in the specific form shown and described may be made within the scope of the claims without departing from the spirit of my invention.

20 I claim:

1. A neckband for ties comprising a band, a compound fastening device at one end of said band, consisting of a loop and an off-set recessed member, a rivet for connecting said 25 fastening device with said band and a hook slidably mounted upon said band at its other end for detachable connection with said loop.

2. The combination of a tie having a body 30 and a knot encircling the same, a neckband having one end extending between a portion

of said knot and the body of the tie, a fastening device secured to the said end of the band adjacent the knot, the said fastening device comprising a recessed portion to the rear of and offset from the said knot, and a looped portion integral with the recessed portion, and means upon the other end of the band to cooperate with the looped portion to fasten the band. 35

3. A neckband for neckties provided with a unit fastening device on one end thereof, the said device consisting of a loop, a recessed member forming an integral continuation of said loop in a lengthwise direction 40 of said unit, said recessed member being offset relatively to said loop in a plane parallel with the surface plane thereof. 45

4. A neckband for neckties provided with a unit fastening device on one end thereof, the said fastening device consisting of a flat loop, a flat member forming an integral continuation of said loop in a lengthwise direction of said unit, said flat member being offset relatively to said loop in a plane 50 parallel with the surface plane thereof and being provided with a transverse recess open at the peripheral edge of said member. 55

In testimony whereof I have hereunto set my hand.

WILL F. SMITH.
